UNITED STATES PATENT OFFICE.

JULIUS ERDOES AND ELMER SAS, OF NEW YORK, N. Y., ASSIGNORS TO THE METALLOGRAPH CORPORATION, OF NEW YORK, N. Y., A CORPORATION OF NEW YORK.

DESIGN FOR AN INKSTAND.

55,851.

Specification for Design.

Patented July 20, 1920.

Application filed December 26, 1919. Serial No. 347,608. Term of patent $3\frac{1}{2}$ years.

To all whom it may concern:

Be it known that we, JULIUS ERDOES and ELMER SAS, citizens of the United States and Hungary, respectively, residing at New York, in the counties of Bronx and New York, respectively, and State of New York, have invented a new, original, and ornamental Design for Inkstands, of which the following is a specification, reference being had to the accompanying drawings, forming part thereof.

Figure 1 is a front elevation of an inkstand, showing our new design; Fig. 2 is a side elevation thereof; Fig. 3 is a top elevation of the same; and Fig. 4 is a section taken on line 4—4 of Fig. 1.

We claim:—

The ornamental design for an inkstand, as shown.

JULIUS ERDOES.
ELMER SAS.
